ADOLPH M. HOLSTEIN, OF SYRACUSE, NEW YORK.

DESIGN FOR A CORNER-PIECE FOR COFFINS AND CASKETS.

Specification for Design.

Patented Jan. 5, 1915.

Application filed September 11, 1914. Serial No. 861,308. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Corner-Piece for Coffins and Caskets, of which the following is a specification, reference being had to the accompanying drawing, forming a part hereof.

In the drawing, Figures 1, 2 and 3 are, respectively, side and front elevations and top plan view of my design for a corner piece for coffins and caskets.

This design of corner piece for coffins and caskets comprises angularly arranged embossed faces having the appearance of a pall with its end portions gathered at points between its side edges and falling in a plurality of folds at opposite sides of the corner piece, and its intermediate portion falling in arc-shaped folds around the angle of the corner piece. Ridges 1 extend one above the other transversely of lengthwise side portions of the corner piece and above the ends 2 of the lower edge of the corner piece, and arc-shaped ridges 3 extend one above the other crosswise of the middle and lower parts of the intermediate lengthwise portion of the corner piece, said ridges extending upwardly from their central parts toward their ends. The upper part of said intermediate lengthwise portion of the corner piece is formed with a hollow substantially T-shaped ridge and depressed surface.

I claim:

The ornamental design for a corner piece for coffins and caskets, substantially as shown and described.

In testimony whereof, I have hereunto signed my name in the presence of two attesting witnesses, at Syracuse, in the county of Onondaga, and State of New York, this 5th day of September, 1914.

ADOLPH M. HOLSTEIN.
